Fig. 7

Fig. 8

Fig. 9

FIGURE 1 is a front perspective view of a typewriter, showing our new design;

FIGURE 2 is a front elevational view thereof;

FIGURE 3 is a top plan view;

FIGURE 4 is a left side elevational view;

FIGURE 5 is a right side elevational view; and

FIGURE 6 is a rear elevational view thereof;

FIGURE 7 is a front perspective view of the typewriter shown in FIGURE 1 wherein the handle of the automatic paper injector has been removed, a series of keys have been extended across the front panel of the hood and a higher supporting base has been employed;

FIGURE 8 is a front elevational view thereof;

FIGURE 9 is a top plan view;

FIGURE 10 is a rear elevational view;

FIGURE 11 is a right side elevational view; and

FIGURE 12 is a left side elevational view thereof.

The dominant features of our design are shown in full lines.

We claim:

The ornamental design for a typewriter, substantially as shown and described.
